UNITED STATES PATENT OFFICE.

OTTO W. HEISE, OF BRIDGEPORT, CONNECTICUT, ASSIGNOR TO MANNING, MAXWELL & MOORE, INC., OF NEW YORK, N. Y., A CORPORATION OF NEW JERSEY.

DIAL FOR INDICATING DEVICES.

Application filed March 30, 1922. Serial No. 548,261.

This invention relates to dials for indicating devices, and also to a method of making the same.

The invention has for its general object

- 5 the improvement and perfection of dial construction resulting in an article which is durable and accurate, and capable of manufacture by a simple process resulting in important production economies.
- 10 Another object is the provision of a dial of paper, or the like, of improved construction in which errors are reduced to a negligible quantity.

Another object is to provide an improved 15 method of manufacture by which uniform dials may be quickly and economically made in small quantities.

Other objects will be in part pointed out 20 in connection with the following detailed description and will be in part obvious as the description proceeds.

In the accompanying drawings in which 25 an illustrative but preferred embodiment of the improved dial is shown,

Figure 1 shows a blank for the dial base; Fig. 2 shows a sheet of photographic paper for the dial face;

Fig. 3 shows the base and face sheet assembled to form a dial blank;

Fig. 4 shows the dial blank with locating openings punched therein; and

Fig. 5 shows the completed dial.

Referring now more particularly to the embodiment disclosed in the drawings, a

35 dial of the type employed for indicating or measuring instruments of various descriptions and constructed in accordance with the invention is shown. This dial comprises a separate base-plate 1 or support,

40 preferably of sheet aluminum or other metal, forming a light but rigid support to which is attached a dial face-sheet 2 of paper or similar material, and having the dial scale and other indicia affixed thereon. This dial

45 sheet is preferably made of photographic paper of good quality, free from discoloring or other injurious agents, and as little subject to stretching or other distortion as possible when subjected to dampening such

50 as by the application of an adhesive substance thereto, or to other distortion under various conditions of manufacture, or in use. It is impossible, however, to secure paper entirely free from such distortions, and this

invention provides means for minimizing errors due thereto, as will fully appear herein-after.

55 The affixing of scale 3 and the other desired indicia to the face-sheet 2, is accomplished by preparing a suitable negative 60 from which they may be readily transferred. Photographically this transfer is conveniently effected by exposing suitable sensitized paper to a photographic negative in a suitable light in the ordinary manner. 65 When made, the face-sheet with its indicia is secured to the metallic supporting base by an adhesive substance, such as cement or glue, which holds the parts securely and permanently in smooth contacting relationship with each other. This forms a composite blank as shown in Fig. 3 from which the dial is subsequently cut as for example by the use of suitable dies, resulting in a 70 light and durable product.

75 The dial above described is made most conveniently and economically, and the errors and inaccuracies due to stretching of the paper, etc., are reduced to a minimum by a process which will now be described. 80 When photographic paper upon which the scale is fixed is subjected to moisture as, for example, when cement or glue is applied, a certain amount of stretching takes place, and this stretching is much greater in the 85 direction of the grain of the paper than across the grain. For example, a certain grade of photographic paper having a dimension in the direction of the grain which measures 5" when dry, will stretch so that 90 this dimension measures about 5 $\frac{1}{8}$ " when glued to the metal; this represents an increase of diameter in this direction of about 2 $\frac{1}{2}\%$. The errors due to this stretching are partially compensated for by making 95 the negative, and consequently the print, enough smaller than the required size to compensate for this stretching. Due to unequal stretching in different directions, however, there will still be a distortion of the 100 print, resulting in errors in the dial scale if not corrected. These errors are minimized and equalized by locating the scale on the completed dial in properly centered 105 position. This is accomplished by so positioning the dial blank for trimming as to compensate and equalize upon the scale the distortion mentioned. The positioning is ef-

2
 fected by means of one or more location spots or indications shown at 4 on the print 2, the negative having a corresponding spot which is transferred to the print in the printing process. This spot will be located preferably at or near the center of curvature of the dial scale, to coincide with the pivotal mounting of the index of the instrument on which the dial is mounted. 10 This spot can be located at some other point on the print, bearing a known relation to the center of curvature of the scale, but it is found more convenient in practice to locate it at the center.

15 It may be desirable to have one or more additional location spots or indications so as to aid in definitely locating the dial for blanking in the punching or other apparatus employed in reducing the blank to final dimensions. Two such spots are indicated at 20 5 and 6 in Fig. 3 of the drawing. Spots 5 and 6 bear a definite relation to spot 4, and these together form indications for definitely positioning the dial with respect to the dies 25 in the punching apparatus. These locating spots are preferably positioned outside the area of the completed dial as shown, but not necessarily so. By this method of locating the position of the indications it will be seen that errors in the scale due to distortion of the dial paper will be equalized and distributed over the scale so as to be reduced to a negligible quantity at any given part of the scale. It will be understood that this 30 method of minimizing errors is applicable to different shapes of dials having indicating scales of different forms and positioned differently on the dial, and is not limited to the form of dial shown in the drawing.

35 41 After the various markings are fixed on the dial face as described, the paper is moistened equally throughout to make it pliable and an adhesive substance is brushed on the back. It is then placed on the face of the metallic base, thoroughly flattened out in position, and the superfluous moisture removed. This provides a composite blank which is then thoroughly dried. It will be understood that at this time the dial is not 45 blanked or punched to size, nor have any screw holes been provided. This is done after the paper has become thoroughly dried and cemented on the metal. The composite blank is first perforated at the locating spots or 50 indications 4, 5 and 6 on the dial face, and the resulting holes, as indicated at 4^A, 5^A and 6^A in Fig. 4, are designed to receive pins or the like, forming a part of the punching apparatus, so as to locate the blank in 55 definite position with respect to the punching dies or other trimming means. Only one of the holes 5^A and 6^A is necessary provided the hole 4^A is adapted to receive one of the

locating pins. It will be understood also that the dial blank may be prepared in some other way than perforating in accordance with the locating indications, such as offsetting or otherwise deforming the metal, or by analogous means. The blanking is thus accomplished so as properly to locate the 65 dial scale relatively to the pointer mounting, and screw holes as 8 and 9 may also be punched at the same time in proper relative relation for securing the dial in position on its instrument. At the time of blanking the 70 opening 7 is formed for receiving the index support, the result of the blanking operation being the completed dial D shown in Fig. 5.

75 After the dial is punched from the dial blank as described, it is thoroughly water-proofed to prevent moisture from penetrating the paper or the joints between the paper and its supporting base. For this purpose dip lacquering is preferable because a complete protective coating is thus secured and no moisture can penetrate to the paper or glue.

80 Having described my invention, what I claim as new and desire to secure by Letters Patent, is:

85 1. A composite blank for use in making dials comprising a piece of stiff sheet material of a size greater than that of the completed dial and constituting a back, and a piece of paper constituting the dial face secured to the back, said paper bearing photographically impressed scale indicia, the composite blank being provided with spaced positioning openings outside the limits of the completed dial for accurately positioning the 90 blank during a subsequent trimming operation.

95 2. That process of making dials for measuring instruments which comprises preparing a photographic print bearing the indicia to appear on the face of the dial, securing the print to a supporting plate by the use of adhesive, and subjecting the composite blank thus formed to a punching operation whereby simultaneously to reduce the print and supporting plate to the size and shape of the 105 completed dial.

110 3. That method of producing dials for measuring instruments which comprises providing a face sheet with scale indications and 115 with one or more location indications, cementing the sheet to a supporting base to form a composite blank, positioning the composite blank relatively to trimming means by reference to the location indications, and trimming surplus material from 120 said blank to reduce the latter to the dimensions of the completed dial.

In testimony whereof I affix my signature.

OTTO W. HEISE.
